UNITED STATES PATENT OFFICE.

DAVID McNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,591, dated February 6, 1883.

Application filed December 13, 1882. Term of patent 3½ years.

To all whom it may concern:

Be it known that I, DAVID McNAIR, of Boston, in the county of Suffolk and State of Massachusetts, have invented a certain new and valuable Design for Carpets, of which the following is a specification.

The nature of my design is fully shown in the accompanying photographic illustration.

The design is composed of the floral groups or sprays, each combined, as shown, with a conventional design or ornamentation and the fragmentary ground ornamentation, all as shown.

I claim—

The design for a carpet, substantially as shown and described.

In testimony whereof I have signed my name to this specification, in the presence of two subscribing witnesses, this 9th day of December, 1882.

DAVID McNAIR.
